UNITED STATES PATENT OFFICE.

WALTER P. MURPHY AND VINTON E. SISSON, OF CHICAGO, ILLINOIS; SAID SISSON
ASSIGNOR TO SAID MURPHY.

RAILWAY-CAR-END CONSTRUCTION.

1,031,571.

Specification of Letters Patent. Patented July 2, 1912.

Application filed August 28, 1911. Serial No. 646,487.

To all whom it may concern:

Be it known that we, WALTER P. MURPHY and VINTON E. SISSON, citizens of the United States, residing at Chicago, in the county of Cook and State of Illinois, have invented certain new and useful Improvements in Railway-Car-End Constructions, of which the following is a specification.

Our invention relates to railway car-end constructions, and the invention has for its object to provide an all metal car end construction of novel character which will be unusually strong and durable throughout, which may be conveniently and economically manufactured, and which shall possess certain other desirable and advantageous features to be hereinafter described and claimed.

The invention is illustrated, in certain typical embodiments, in the accompanying drawings, wherein—

Figure 1 is an end elevation of the body of a railway freight car; Fig. 2, a sectional view taken on line 2—2 of Fig. 1, looking in the direction of the arrow; Fig. 3, a sectional plan taken on line 3—3 of Fig. 1; Fig. 4, a view, in perspective, of a preferred form of the upper end plate; Fig. 5, a similar view of the lower plate, Figs. 6 and 7 are fragmentary sectional views taken through the joint between the upper and lower plates illustrating modified constructions for providing a waterproof joint; Fig. 8, a fragmentary vertical section illustrating a modification; Fig. 9, an end elevation of a car illustrating a modified form of metal end construction; Fig. 10, a sectional view taken on line 10—10 of Fig. 9, looking in the direction of the arrows; Figs. 11 and 12, sectional plans taken respectively on lines 11—11 and 12—12 of Fig. 9, Fig. 13, a view, in perspective, of a preferred form of upper end plate for this type of end construction, Fig. 14, an enlarged fragmentary vertical longitudinal sectional view taken centrally of the car to illustrate particularly the connection between the upper end plate and the roof structure; Fig. 15, a fragmentary sectional view similar to that shown in Fig. 14 illustrating a modification; Fig. 16, an end elevation of a car showing a somewhat different construction of the metal end; Fig. 17, a vertical sectional view taken

on line 17—17 of Fig. 16, and Figs. 18 and 19, sectional plan views taken on, respectively, lines 18—18 and 19—19 of Fig. 17.

Like characters of reference indicate like parts in the several figures of the drawings.

It has been proposed to construct a car end of a single sheet of metal dished outwardly and formed with concentrically arranged circular corrugations, the latter for the purpose of giving strength and rigidity to the plate. This construction, however, is very difficult and costly to manufacture owing to the size of the sheet and the configuration which must be given to it by the pressing or stamping operation. Moreover, a car end formed from a single sheet necessitates, in practice, making the sheet throughout as thick and heavy as that portion of the end of the car has to be which must stand the greatest strains, that is to say, the lower part. This means that an unnecessary amount of metal is used and the end is made unnecessarily heavy. Furthermore, when the end of the car is substantially rectangular, in the case of an ordinary box car, the provision of the plate with circular corrugations leaves the corners of the plate without reinforcement. The necessity for strength is just as great at the corners of the plate, and particularly the lower corners, as at the middle. Our invention provides an all metal end construction which, by obviating these objectionable features, gives increased strength and durability and at the same time reduces manufacturing cost.

Referring first to the form of end construction shown in Figs. 1 to 5 inclusive, 25 designates one of the end sills of a railway box car, 26, 26, the corner posts, 27 the flooring of the car, and 28 the roof shown as supported on the ridge pole 29 and pur- 90 lins 30. The car construction shown is a familiar and usual type which, of course, might be modified, if occasion demanded, without departure from our invention; the names given to the various constructional elements being used with that understanding. 31 designates a metal plate formed with flanges 32 which overlap the corner posts 26 and are bolted thereto by the bolts 33, the outer corners of the posts being cut 95 away so that the flanges 32 and their bolts 100 105

33 come within the sheathing 33^a of the car. This protects the attachment of the plate to the post. The lower edge of the plate 31 is bolted to the end sill 25 by the bolts 34. 35 is an upper plate which is preferably considerably thinner and lighter than the plate 31 and which is formed with the flanges 36 which overlap and are bolted to the corner posts 26 as in the case of the flanges 32 on the lower plate. Plates 31 and 35 are preferably formed at their meeting edges with the outwardly projecting flanges 37, 38 which are secured together by the rivets 39. The flange 38 on plate 35 is preferably wider than flange 37 on the lower plate and is preferably formed with the depending lip 38^a. By this arrangement water cannot enter the car along this joint between the plates. In Fig. 6 the flange 38^b projects beyond the flange 37^b on the lower plate but has no lip. In Fig. 7 the flanges 37, 38^c are bent downwardly. The plates are formed with corrugations 40 which are preferably horizontal and extend substantially to the margins of the plates overlapping the corner posts. While the corrugations are necessarily tapered down at their extremities, except at these extreme points they are preferably of substantially the same depth throughout. By forming the plates in this manner the entire portion of the plates inside the framework of the car is uniformly reinforced. No part is appreciably weaker or stronger than any other part. This is important because the end of a car is not in the situation of a beam having the heaviest load at the point midway between its supports. The side portions of a car end are as likely to be subjected to heavy strains as the center portion, all depending upon the character of the contents of the car. However, the heavier articles, such, for example, as rails, pipe and the like, are sure to be placed in the lower part of the car. If the car is loaded up to the roof the upper part of the load is made up of lighter articles. It is therefore possible if the end is made in two or more sections (obviously, if desired, it might be made up of more than two plates) to economize in metal and save in dead weight by forming the upper plate of lighter material than the lower one. Preferably the upper plate 35 is formed with 55 an inwardly projecting flange 41 which carries the end of the roof structure of the car doing away with the necessity of the usual end plate.

In the construction shown in Figs. 1 to 5 inclusive, the ridge pole 29 and purlins 31 are supported by the flange 41, the ridge pole being shown as secured to the flange by means of an angle clip 42 attached to the flange 41 by rivet 43 and to the ridge pole by bolts 44. If desired the flange 41

may be omitted and the usual end plate employed as will be hereinafter described.

Fig. 8 illustrates a modification in the form of the lower plate. Here the lower plate designated 45 is formed with an inturned flange 46 at its lower edge which is secured by vertical bolts 47 to the end sill 25.

Figs. 9 to 14 illustrate a somewhat different embodiment of our invention. In this construction the plates 48 and 49 are bowed or curved outwardly (this convexity being substantially uniform from top to bottom) instead of being flat as in the form of the invention previously described. These figures also illustrate a different arrangement of the strengthening corrugations; which arrangement though shown in connection with the curved plates might be used with plates which are flat. The formation of corrugations of considerable depth and extending quite close to the edge of a metal plate is an operation which, while feasible, is likely to be somewhat difficult owing to the tendency of the metal to draw and distort the plate. To overcome this difficulty the plates shown in Figs. 9 to 14 inclusive are formed with a series of centrally arranged corrugations 50, preferably widest at their middle points and tapering down toward the ends, which preferably do not 95 extend very close to the edges of the plate. Between these corrugations at each side of the plate is a series of similarly tapered corrugations 51 which project outwardly beyond the extremities of the corrugations 50. By this arrangement the stamping of the corrugations is facilitated, because the main set of corrugations 50 do not have to be carried out quite so close to the edges of the plates; while the portions of the plates 105 within the framework of the car end are given a reinforcement which is substantially uniform throughout. The plates 48 and 49 are shown as formed with flanges 52 which overlap the corner posts and the upper plate 49 is formed with an inwardly projecting flange 53 which supports the roof structure in the manner described in connection with the construction shown in Figs. 1 to 5 inclusive. In Fig. 13 we have shown a construction utilizing the ordinary end plate which is here designated 54. The upper sheet metal element 55 of the end structure is secured to the wooden end plate by bolts 56.

A construction which is modified with respect to the curvature of the end is illustrated in Figs. 16 to 19 inclusive. An order of the Interstate Commerce Commission having for its purpose to insure a sufficient 125 end ladder clearance provides that no part of the car above the end sills within 30 inches from the side of the car shall extend to within twelve inches of a vertical plane parallel with the end of the car and passing 130

through the inside face of the coupler knuckle. If the end of the car is convex on a segment of a cylinder, the inner corner of the end ladder may, depending on the radius 5 of the curve, project out for a considerable distance beyond the farthest projecting point of the car end within the thirty inches. This means a shortening of the car body in order to comply with the order of 10 the Interstate Commerce Commission. It may be desirable for obvious reasons to make the plates convex and this convexity may be obtained without unnecessarily shortening the car by forming the plates on 15 a reverse curve that is to say so as to provide depressions at the sides of the plates on each side of the central bulging or protruding portion of the end structure. 57, 58 (Figs. 16 to 19 inclusive) designate plates 20 so formed. 59 designates the ladder. It will be seen that the inner corner of the ladder with this configuration of plate projects very little farther than the outer corner.

25 We have shown and described the invention as applied to a box car of usual construction. It will be understood that the term "box car" is used in a broad signification to include, for example, caboose cars or 30 other house cars. The invention is applicable to car constructions other than the particular construction shown.

We claim:

1. The combination with an end sill and 35 corner posts of a railway box car, of a metal end comprising upper and lower plates formed with overlapping portions which are secured together, said plates being secured to the end sill and corner posts and being 40 formed with transversely corrugated portions the corrugations of which extend substantially to the corner posts so as to uniformly reinforce the entire portion of the car end between the corner posts.

45 2. The combination with an end sill and corner posts of a railway box car, of a metal end comprising upper and lower plates formed with substantially parallel corrugations and secured together and to said corner 50 posts and end sill; the lower plate being formed of thicker metal than the upper plate, substantially as and for the purpose described.

55 3. The combination with an end sill and corner posts of a railway box car, of a metal end comprising upper and lower corrugated plates formed with outwardly projecting flanges at their meeting edges, the flange on the upper plate projecting beyond that on the lower, for the purpose specified, means 60 for securing said flanges together, and means for securing the plates to the end sill and corner posts.

65 4. The combination with an end sill and corner posts of a railway box car, of a metal

end comprising upper and lower corrugated plates formed with outwardly projecting flanges at their meeting edges, the flange on the upper plate projecting beyond that on the lower plate and being formed with a 70 downturned lip for the purpose specified, means for securing said flanges together, and means for securing the plates to the end sill and corner posts.

5. The combination with an end sill, 75 corner posts and roof structure of a box car, of a metal end comprising upper and lower corrugated plates secured together and to the end sill and corner posts; said upper plate being formed with an inwardly projecting flange at its upper edge which supports the end of the roof structure in place of the usual end plate.

6. The combination with an end sill, 85 corner posts and roof structure of a box car, 80 of a metal end comprising upper and lower plates formed with outwardly extending flanges at their meeting edges which are secured together, the flange on the upper plate projecting beyond that on the lower plate 90 for the purpose specified, the lower plate being made of thicker metal than the upper plate, and the upper plate being formed at its upper edge with an inwardly extending flange to support the roof structure in place 95 of the usual end plate, said plates being provided with flanges overlapping and secured to the corner posts and with transverse corrugations which extend substantially to the corner posts so as to uniformly reinforce the 100 entire portion of the end between said corner posts.

7. The combination with an end sill and corner posts of a railway box car, of a sheet metal end secured to said sill and posts 105 which is convex, substantially uniformly from top to bottom, and formed with transverse corrugations.

8. The combination with an end sill and corner posts of a railway box car, of a metal 110 end comprising a corrugated sheet metal plate formed with flanges on its vertical edges, and bolts securing said flanges to the corner posts; said corner posts being recessed at the places of attachment of said 115 plate so as to bring the flanges of the plate and the attaching bolts within planes of the sheathing of the car, substantially as and for the purpose described.

9. The combination with an end sill, corner posts and roof structure of a box car, 120 of a metal end comprising upper and lower corrugated plates formed with outwardly extending flanges at their meeting edges 125 which are secured together, the flange on the upper plate projecting beyond that on the lower plate, for the purpose specified, the lower plate being made of thicker metal than the upper plate and the upper plate being formed at its upper edge with an in- 130

- wardly extending flange to support the roof structure in place of the usual end plate; said plate being provided with flanges overlapping the corner posts, and bolts securing said flanges to said posts, the posts being recessed at their outer corners so as to bring said flanges and attaching bolts within the planes of the sheathing of the car, substantially as described.
10. 10. The combination with the body of a railway car, of an all-metal end structure consisting of upper and lower metal plates, the lower plate being thicker than the upper plate, provided at their adjacent edges with means for securing them together and at their outer edges with flanges for securing them to the car body.
11. 11. The combination with the body of a railway car, of an all-metal end structure consisting of upper and lower metal plates, the lower plate being thicker than the upper plate, provided at their adjacent edges with means for securing them together and at their outer edges with flanges for securing them to the car body; said plates being formed with corrugations extending from substantially one side of the car to the other so as to uniformly reinforce the entire portion of the car end against which the cargo is thrust.
12. 12. The combination with the body of a railway car, of an all-metal end structure consisting of upper and lower metal plates provided at their adjacent edges with means for securing them together and at their outer edges with flanges for securing them to the car body, said plates being formed with corrugations extending from side to side of the car and terminating within the planes of the side walls of the car so as to uniformly reinforce that portion of the end structure against which the cargo is thrust.
13. 13. The combination with the body of a railway car, of an all-metal end structure comprising upper and lower plates formed with projecting flanges at their meeting edges, the flange on one of said plates projecting beyond that on the lower so as to water proof the joint between said plates, means for securing said flanges together, and means for securing the plates to the car body.
14. 14. The combination with the body of a railway car, of an all-metal end structure comprising a sheet metal plate formed with flanges on its vertical edges which overlap and are secured to the side wall structures of the car, said side wall structures being recessed at the place of attachment of said plate so as to bring the flanges of the plate within the planes of the sheathing of the car, substantially as and for the purpose described.
15. 15. The combination with the body of a railway car, of an all-metal end structure consisting of upper and lower metal plates provided at their adjacent edges with means for securing them together and at their outer edges with flanges for securing them to the car body, said plates being formed with corrugations extending from side to side of the car so as to uniformly reinforce that portion of the end structure against which the cargo is thrust.
